MOTION PICTURE CAMERA

Clare E. Hodgman, Mamaroneck, N.Y., assignor to General Aniline & Film Corporation, New York, N.Y., a corporation of Delaware

Filed May 5, 1961, Ser. No. 65,033

Term of patent 14 years

(Cl. D61—1)

FIG. 1

Des. 196,009

PAGE 2

FIG.3

FIG.2

FIG.4

FIG.5

FIG. 1 is a perspective view of the front and one side of the motion picture camera showing my new design;
FIG. 2 is a front view thereof; and

FIG. 3 is a side elevational view taken from the opposite side shown in FIG. 1;

FIG. 4 is an elevational view showing the back of the motion picture camera;

FIG. 5 is a bottom view thereof.

I claim:

The ornamental design for a motion picture camera, substantially as shown.
